UNITED STATES PATENT OFFICE

ALEXANDER MARTINEK, OF BROOKLYN, NEW YORK, ASSIGNOR TO PRAGER CO. INC.,
OF BROOKLYN, NEW YORK, A CORPORATION OF NEW YORK

PROCESS AND MACHINE FOR MANUFACTURING WALL PAPER AND THE LIKE

Application filed March 13, 1929. Serial No. 346,583.

This invention relates generally to new and useful improvements in a process and a machine for manufacturing paper and the like.

5 The invention has for an object the provision of a process and a machine of the class described which is of simple arrangement, dependable in use and efficient in action, and which may be applied and manufactured at 10 a reasonable cost.

Up to the present time, so called ink-embossing has been done only in one way; namely by applying ink, color or bronze in the depressed portion of an embossing design in one 15 operation when the material, such as paper, imitation leather, oilcloth, cardboard, aluminum, tinfoil etc. is being embossed.

This process has been in use for many years in all sorts of industries and is done by 20 a so called "inking attachment" on the embossing machine, which conveys, thru the use of a gelatine or rubber roller, the ink to the highest points of an engraved steel roller used in embossing the material, thereby applying 25 the same on the material to the depressed portions of the design.

The invention proposes a process and a machine for applying in one single operation a color, ink or bronze on the raised parts 30 of the embossed material in addition to the color, ink or bronze normally applied in the depressed portions. The process proposes the drawing of the normally ink-embossed material between an idler roller, and an inking 35 roller slightly spaced from the idler roller so that the rear faces of the depressed portions of the material engage against the idler roller, and the front faces of the raised portions engage against the inking roller and receiving 40 ink, color or bronze.

In addition, the invention proposes a machine provided with an idler roller for supporting the ink-embossed material with the raised portions outwards and an inking roller 45 slightly spaced from the idler roller for engaging against the raised portions. The various rollers should be adjustably arranged so that they may be properly "set" for inking materials in which the embossed design is of 50 different heights or in which the material it-

self is of different thicknesses. The invention also proposes an attachment for an ink-embossing machine capable of delivering ink-embossed material with the ink disposed in the depressed portions of the embossing, the 55 said attachment should consist of an idler roller for guiding the material with the raised portions outwards, and an inking roller slightly spaced from the idler for engaging against the raised portions only. In this attachment the rollers should preferably be 60 adjustably arranged.

For many years past, there has been in use a so called "combination printing and embossing machine" which inks the depressed 65 portions of an embossing design and in addition prints one or more colors by the use of "print rollers" made of wood, brass, felt or metal, upon the raised portions of the embossing design, but this printing is accomplished in a customary printing fashion. For properly understanding the difference between the instant invention and this machine, an "inking roller" as used in this specification and in the claims will be construed to 70 mean a roller having a smooth surface without any raised or depressed portions and capable of holding ink throughout its entire surface, and a "printing roller" defined as a roller in which there is a raised design upon 75 its surface which is adapted for receiving the ink and printing the same, the lowered portions on the roller not receiving ink and doing no printing.

The printing process and machine immediately before mentioned cannot be used for applying ink, color or bronze on all the raised portions of an embossing design because it is only adapted to print in fairly broad places, due to the fact that the print rollers cannot 80 be kept in accurate printing "set". The present practice arranges the design upon the printing roller in large areas so that should the printing register be slightly off, it will 85 not be very noticeable that printing has also been done on the depressed portions of the printing design.

The embossing of the material causes the material to stick within portions of the engraved steel roller used in doing the emboss- 100

ing and this causes continual jumping of the material which materially interferes with a proper "set" of the printing rollers. For this reason, it is necessary for a man to continually watch the machine during its operation and continually keep adjusting the "set" of the printing roller for maintaining its proper printing position relative to the material being printed. This conclusively points out that it would be utterly impossible to have a print roller made to cover all raised portions of an embossing design if such design consists of a plurality of closely spaced and comparatively small raised portions, without reaching low spots and coming out of fit with every revolution of the machine.

The "printing roller" process for printing the raised portions of an embossing design necessitates the exceedingly slow running of the machine, due to the fact that the printing rollers must be kept in fit as near as possible, requiring continual manual adjustments, but according to the instant invention ink may be applied to the raised portions of an embossing design at the same high speed at which the present day ink embossing is done on the depressed portions.

Since the machine using the instant invention can operate at greater speeds than machine using "printing rollers", this in itself is an important feature in that the labor cost of the material is materially reduced. In addition, according to the instant invention it is not necessary to make a drawing and then cut a printing roller according to this drawing in wood, brass or felt and at all times keep in mind the producing of such a design that could be successfully printed without large spoiling of material attempted to be printed due to bad registering.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a side elevational view of a machine constructed according to this invention.

Fig. 2 is a fragmentary enlarged side elevational view of the idler roller and the inking roller of the machine, the material being treated is shown in sectional view between these rollers.

The reference numeral 10 indicates generally the frame of a machine having a steel roller 11 engraved with an embossing design and coactable with a paper roller 12 for producing embossing. Wall covering material 13 is shown running between these rollers and is supplied from a material supply roll 14 and delivered upon a finished material roll 15.

A means for inking the depressed portions

of the embossing design consists of an inking roller 16 engaging against the steel engraved embossing roller 11 and receiving ink from an intermediate roller 17 in contact with a primary roller 18 engaging in an ink tray 19. The relative positions of the rollers 16, 17 and 18 are adjustable by controls indicated generally by numerals 20. A control 20^a serves to permit adjusting of the pressure between the steel roller 11 and paper roller 12, this arrangement being common on present day machines. It is customary that the primary rollers 18 be of metal, the intermediate roller 17 of rubber, and the inking roller 16 of gelatine or rubber.

The inking attachment for inking the raised portions of the embossing design is secured upon the rear of the frame 10, and consists of a bracket 21 supporting an idler roller 22, an inking roller 23, an intermediate roller 24 and a primary roller 25. The material 13 passes between the idler 22 and the inking roller 23. The primary roller 25 engages in an ink tray 26 and is in contact with the intermediate roller 24 which in turn engages against the inking roller 23. The relative positions of the rollers 22, 23, 24 and 25 may be adjusted by controls indicated generally by numeral 27.

It is pointed out that the material as it leaves the roll 14 and passes between the steel engraved roller 11 and the paper roller 12 becomes embossed and inked by the said steel roller 11. The depressed portions are towards the bottom and the raised portions towards the top and in this condition the material passes over the idler 22. Fig. 2 clearly illustrates this, the depressed portions in this figure being designated by reference numeral 28 and the raised portion by numeral 29.

It should be noticed that the inking roller 23 merely touches the outer faces of the raised portions 29 and for this reason the outer faces receive the ink while the depressed portions 28 do not. For proper operation the correct positioning of the rollers 22 and 23 is necessary. Should the rollers be too close together, the raised portions of the design may be flattened and perhaps some of the ink deposited upon the depressed portions, while in the event that the rollers are spaced apart too great a distance, the raised portions may not receive any ink at all. Proper positioning of the rollers may be accomplished by manipulation of the controls 27. The idler roller should preferably be made of rubber, the inking roller and the intermediate roller should also be of rubber, but the primary roller should be metallic.

While I have illustrated and described my invention with some degree of particularity, I realize that in practice various alterations therein may be made. I therefore reserve the right and privilege of changing the form of the details of construction or otherwise

altering the arrangement of the correlated parts without departing from the spirit or the scope of the appended claims.

Having thus described my invention, what I claim as new, and desire to secure by United States Letters Patent is:—

1. A process for manufacturing wall paper and the like, which consists in applying ink, color, or bronze in the depressed portions of an embossing design in one operation while the material is being embossed, then guiding the material between an idler roller and an inking roller slightly spaced from the idler roller, so that the raised portions of the material engage against the inking roller and receive ink, color or bronze.

2. A process for manufacturing wall paper and the like, which consists in applying ink, color or bronze in the depressed portions of an embossing design in one operation while the material is being embossed, then guiding the material between an idler roller and an inking roller slightly spaced from the idler roller, so that the depressed portions of the material engage against the idler and the raised portions of the material engage against the inking roller and receive ink, color or bronze.

3. A process for manufacturing wall paper and the like, which consists in drawing the wall covering material in an ink-embossed condition, between an idler roller and an inking roller slightly spaced from the idler roller so that the rear faces of the depressed portions of the material engage against the idler roller, and the front faces of the raised portions engage against the inking roller and receive ink, color or bronze.

4. A process for manufacturing wall paper and the like, which consists in drawing the wall covering material in a printed and embossed condition, between an element and an inking roller slightly spaced from the element so that the rear faces of the depressed portions of the material engage against the element, and the front faces of the raised portions engage against the inking roller and receive ink, color or bronze.

5. A process for manufacturing wall paper and the like, which consists in drawing the wall covering material in an embossed condition, between an idler roller and an inking roller slightly spaced from the idler roller so that the rear faces of the depressed portions of the material engage against the idler roller, and the front faces of the raised portions engage against the inking roller and receive ink, color or bronze.

6. A machine for manufacturing wall paper and the like, comprising means for embossing and simultaneously inking on the depressed portions of material passed thru the machine, an idler roller for supporting the ink-embossed material with the raised portions outwards, an inking roller slightly

spaced from the idler roller for engaging against the raised portions, and means for supplying ink, color or bronze to the inking roller for depositing it upon the raised portions of the said material.

7. A machine for manufacturing wall paper and the like, comprising means for embossing and simultaneously inking on the depressed portions of material passed thru the machine, an idler roller for supporting the ink-embossed material with the raised portions outwards, an inking roller slightly spaced from the idler roller for engaging against the raised portions, and means for supplying ink, color or bronze to the inking roller for depositing it upon the raised portions of the said material, said inking roller being movable and adjustable for providing proper spacing relative to the idler.

8. A machine for manufacturing wall paper and the like, comprising means for embossing and simultaneously inking on the depressed portions of material passed thru the machine, an idler roller for supporting the ink-embossed material with the raised portions outwards, an inking roller slightly spaced from the idler roller for engaging against the raised portions, and means for supplying ink, color or bronze to the inking roller for depositing it upon the raised portions of the said material, said idler and inking rollers being adjustable relative to each other for providing proper spacing.

9. A machine for manufacturing wall paper and the like, comprising means for embossing material passed thru the machine, an idler roller for supporting the embossed material with the raised portions outwards, an inking roller slightly spaced from the idler roller for engaging against the raised portions, and means for supplying ink, color or bronze to the inking roller for depositing it upon the raised portions of the said material.

10. A machine for manufacturing wall paper and the like, comprising means for embossing and simultaneously inking on the depressed portions of material passed thru the machine, an element for supporting the ink-embossed material with the raised portions outwards, an inking roller slightly spaced from the element for engaging against the raised portions, and means for supplying ink, color or bronze to the inking roller for depositing it upon the raised portions of the said material.

11. A machine for manufacturing wall paper and the like, comprising means for embossing and simultaneously inking on the depressed portions of material passed thru the machine, an idler roller for supporting the ink-embossed material with the raised portions outwards, an inking roller slightly spaced from the idler roller for engaging against the raised portions, means for adjusting the relative spacing of the idler and ink-

ing rollers, and means for supplying ink, color or bronze to the inking roller for depositing it upon the raised portions of the said material.

12. A machine for manufacturing wall paper and the like, comprising means for embossing and simultaneously inking on the depressed portions of material passed thru the machine, an idler roller for supporting the ink-embossed material with the raised portions outwards, an inking roller slightly spaced from the idler roller for engaging against the raised portions, and means for supplying ink, color or bronze to the inking roller in controlled amounts, for depositing it upon the raised portions of the said material.

13. An attachment for a manufacturing machine capable of delivering ink-embossed material with the inked portions disposed in the depressed portions of the embossing, comprising an idler roller for guiding the material with the raised portions outwards, an inking roller slightly spaced from the idler for engaging against the raised portions only, and means for supplying ink, color or bronze to the inking roller for depositing it upon the raised portions of the said material.

14. An attachment for a manufacturing machine capable of delivering ink-embossed material with the inked portions disposed in the depressed portions of the embossing, comprising an element for guiding the material with the raised portions outwards, an inking roller slightly spaced from the element for engaging against the raised portions only, and means for supplying ink, color or bronze to the inking roller for depositing it upon the raised portions of the said material.

15. An attachment for a manufacturing machine capable of delivering ink-embossed material with the inked portions disposed in the depressed portions of the embossing, comprising an idler roller for guiding the material with the raised portions outwards, an inking roller slightly spaced from the idler for engaging against the raised portions only, means for adjusting the relative spacing of the idler and inking rollers, and means for supplying ink, color or bronze to the inking roller for depositing it upon the raised portions of the said material.

Signed at New York in the county of New York and State of New York this 4th day of March A. D. 1929.

55 ALEXANDER MARTINEK.
